ULTRAVIOLET WATER PURIFIER

Albert Young, Sands Point, N.Y., assignor to Ultra-dynamics Corporation, Paterson, N.J., a corporation of Delaware

Continuation-in-part of design application Ser. No. 3,264, July 29, 1966. This application June 10, 1968, Ser. No. 12,690

Term of patent 14 years

Int. Cl. D23—01

U.S. Cl. D23—3

FIG.1**FIG.2****FIG.3****FIG.4**

FIG. 5

FIG. 6

FIG. 7

FIG. 8

FIG. 1 is a top plan view of an ultraviolet water purifier, showing my new design;

FIG. 2 is a side elevational view thereof;

FIG. 3 is a view of one end thereof;

FIG. 4 is a view of the other end thereof;

FIG. 5 is a front perspective view of a modified embodiment of the ultraviolet water purifier illustrated in FIG. 1;

FIG. 6 is a rear perspective thereof;

FIG. 7 is a front perspective of a further modified embodiment of the water purifier illustrated in FIG. 1; and

FIG. 8 is a perspective view as seen from the opposite side of FIG. 7.

This is a continuation-in-part of design application Ser. No. D. 3,264 filed July 29, 1966, and now abandoned.

I claim:

The ornamental design for an ultraviolet water purifier, as shown and described.
